UNITED STATES PATENT OFFICE.

EUGENE H. HOLDEN, OF KEENE, NEW HAMPSHIRE, ASSIGNOR OF ONE-HALF TO GEORGE H. GIFFIN, OF KEENE, NEW HAMPSHIRE.

ROTARY ENGINE.

No. 805,958.

Specification of Letters Patent.

Patented Nov. 28, 1905.

Application filed May 15, 1905. Serial No. 260,520.

To all whom it may concern:

Be it known that I, EUGENE H. HOLDEN, a resident of Keene, in the county of Cheshire and State of New Hampshire, have invented 5 certain new and useful Improvements in Rotary Engines; and I do hereby declare the following to be a full, clear, and exact description of the invention, such as will enable others skilled in the art to which it pertains 10 to make and use the same.

This invention relates to rotary engines, and has for its object to provide a simple, economically-constructed, smoothly-running, and efficient engine of the type named.

15 The invention consists in the construction hereinafter described and set forth.

In the accompanying drawings, which form a part of this specification, Figure 1 is a side elevation of the engine looking toward the 20 left of Fig. 2. Fig. 2 is an end elevation looking toward the left of Fig. 1, the pulley, base, and pedestals being omitted. Fig. 3 is a section on line 3 3 of Fig. 1, the view being toward the left of said latter figure. Fig. 4 25 is a perspective of an abutment. Fig. 5 is a central longitudinal section of a steam-admission valve and casing on a larger scale and the valve turned to open position, and Fig. 6 is a partial central section of the cylinder.

30 Numeral 1 denotes a base, 1^a pedestals to support shaft-bearings, and 1^b pedestals supporting the steam-cylinder 2. This cylinder is provided with extensions 3 to operatively 35 contain steam-abutments 4. These are approximately semicylindrical in form, as shown, and are fixed to shafts 5, having journal-bearings 6 in the ends of the cylinder extensions. Each of the shafts 5 has at each 40 end an arm or crank 7, operatively connected by a pivoted rod 8 to a crank-arm 9 on a valve-stem 10, controlling steam admission through pipe 11 and inlet 12 of valve 13, one valve being above and the other below the 45 level of the abutment-shafts, as represented. The cranks 7 at one end of the engine are situated at right angles to those at the other end to avoid dead-centers.

14 denotes the valve-casings, and 14^a live- 50 steam-admission ports.

13^c denotes a stud on the end of the valve having a suitable seat or cavity in the valve-casing, and 13^d is a cross-bar connecting the valve and its stem.

The cranks 7 are each pivotally connected 55 to a rod 15, fixed to one of two eccentric-straps 16 on eccentric 17, fixed to a piston-shaft 18, having bearings 18^a in the cylinder-heads and provided with a pulley 19. The brasses 20, in which crank-pins 21 have bearing, can be backed by springs 22 to permit variation in the operative length of the eccentric-arms 15. Other means known to be suitable for such general purpose may be employed.

60 Numeral 23 denotes a piston on shaft 18 and preferably made hollow with partitions or webs substantially as represented to insure lightness and strength. The abutments are similarly formed for the same and 65 other reasons. The piston is ovoid in cross-section and eccentrically secured on the shaft, as indicated. The shape and dimensions of this piston and of each abutment are such and their period of rotation is so provided for that two longitudinal lines of the 70 piston will at all times be in contact with two abutments or with an abutment and the interior of the main body of the cylinder, so that admitted steam expands behind the 75 piston and drives it and its shaft. The abutments and abutment partitions or diaphragms are provided with ports for the admission of exhaust-steam. The ports situated in the abutment-peripheries are not 80 alined circumferentially with live-steam ports. Only one-half of the abutment-ports are operative for exhausting. They are indicated by 25. The other half (indicated by 85 25^a) admit steam to relieve the piston and 90 avoid compression. The abutments and piston are of the same length as the cylinder and its extensions on the interior.

24 denotes exhaust-ports in a cylinder-head to permit the exit of the exhaust through the 95 open ends of the abutments. The exhaust enters the abutments through the ports 25, situated on one side of a central web or partition 26.

Packings of any approved form extending 100 lengthwise the abutments and piston and connected with radially-situated packings at their ends in any usual or approved manner are denoted by 27.

The admission-valves 13 have stems 13^a 105 extending lengthwise through the valve and the valve-casings 14. They are provided at each end with a crank-arm 13^b pivotally con-

nected to a rod 28, which is loosely connected to a crank 7, and thereby mediately connected to an eccentric-rod 15.

Figs. 1, 2, and 3 correspond to the same 5 situation of the several parts, and the arrows indicate the directions in which pistons, abutments, and valves are supposed to be moving. As indicated, steam has been cut off by the upper admission-valve 13 and is about to 10 be admitted by the lower one. Steam is expanding above the piston, and the exhaust has escaped through the left-hand abutment. The abutments move oppositely to the piston and the upper line of the one at the right continues in contact with the piston until its periphery comes into such contact. The lower valve moving as indicated by the arrow will be 15 in situation to admit steam through port 14^a as soon as the packed line of the piston passes 20 the port. At this moment steam-pressure acts upon the concave or entire face of the abutment equally on opposite sides of the abutment-shaft. This equilibrium would be 25 destroyed as soon as the periphery of the upper exterior of the abutment passes within its cylinder extension or casing; but at such time and for a brief moment live steam enters the abutment through ports 25^a to effect 30 a counterbalance of pressure on the abutment-shaft and cushion the abutment. The parts being continuously driven without 35 change of direction, steam is next admitted through the upper valve and exhausted through the abutment immediately below it in like manner as described with reference to the other valve and abutment.

To avoid complicating and obscuring the drawings and unnecessarily extending the description, the steam admitting and exhausting 40 devices necessary for reversing the engine are not shown, such matter being regarded as obvious.

What I claim is—

1. The combination of the cylinder having 45 the extensions provided with exhaust-ports, the piston, the abutments provided with openings for the exhaust-steam, said piston and abutments having each the same length as the cylinder interior, the piston-shaft, an 50 eccentric on said shaft at each end of the cylinder, abutment-shafts, steam-admission valves, valve-stems, connections between the eccentrics and the abutment-shafts, and connections between said shafts and the valve- 55 stems, all substantially as set forth whereby upon admission of steam the piston and abutments are driven oppositely, steam exhausted and fresh live steam admitted and exhausted continuously.
- 60 2. In a rotary engine, the combination of the cylinder and cylinder extension, with a piston, means for admitting and exhausting steam, an abutment having a peripheral opening for exhaust and an open end and the cylinder extension having a coacting exhaust-

port and a distinct steam-admission port outside the abutment.

3. In a rotary engine, the combination of the cylinder and cylinder extension, with a piston, means for admitting and exhausting steam, and an abutment having a peripheral opening for exhaust and an open end, and the cylinder extension having a coacting exhaust-port, said abutment having also ports communicating with the expanding live steam, and a distinct steam-admission port outside the abutment. 75

4. In a rotary engine, the combination of the cylinder and piston, with hollow rotating abutments of approximately semicylindrical form, each having a face entire to receive live-steam pressure on opposite sides of the abutment-shaft and having on its periphery opposite said face live-steam ports to cushion the abutment, and exhaust-ports to transmit steam to an exhaust-port in the cylinder. 80

5. In a rotary engine, a piston, hollow rotating abutments having each an approximately semicylindrical form, a partition dividing the abutment hollow into two parts, 90 ports adapted to admit live steam on one side of said partition, ports to admit exhaust-steam on the other side of the partition, and an exhaust-port in the cylinder to coact with the exhaust-ports of the abutment. 95

6. In a rotary engine, the combination of the cylinder, piston, piston-shaft, abutments, abutment-shafts, valves, valve-stems, said stems having crank-arms, and the abutment-shafts having crank-arms at each end, 100 an eccentric on the piston-shaft at each end of the cylinder, and connections for rotating the abutments from the eccentrics and immediately rotating the valves.

7. In a rotary engine, the combination of 105 the cylinder, piston, piston-shaft, abutments, abutment-shafts, valves, valve-stems, said stems having crank-arms, and the abutment-shafts having crank-arms at each end, an eccentric on the piston-shaft at each end 110 of the cylinder, and connections for rotating the abutments from the eccentrics and immediately rotating the valves, said abutment-shaft cranks being set at an angle to each other to avoid dead-centers. 115

8. In a rotary engine, the combination of 120 the cylinder, piston, piston-shaft, abutments, abutment-shafts, valves, valve-stems, said stems having crank-arms, and the abutment-shafts having crank-arms at each end, an eccentric on the piston-shaft at each end 125 of the cylinder, and connections for rotating the abutments from the eccentrics and immediately rotating the valves, said connections comprising rods loosely connecting the valve-stems and abutment-shaft cranks, and rods connecting the latter cranks with the eccentrics.

9. In a rotary engine, the combination of 130 the cylinder, piston, piston-shaft, abut-

ments, abutment-shafts, valves and valve-stems, said stems having crank-arms, and the abutment-shafts having crank-arms at each end, an eccentric on the piston-shaft at each end of the cylinder, and connections for rotating the abutments from the eccentrics and meditately rotating the valves, said connections comprising rods loosely connecting the valve-stems and abutment-shaft cranks, and rods connecting the latter cranks with the eccentrics, said latter rods having each its effective length variable.

10. In a rotary engine, the combination of the cylinder, piston, piston-shaft, abutments, abutment-shafts, valves and valve-stems, said stems having crank-arms, and the abutment-shafts having crank-arms at

each end, an eccentric on the piston-shaft at each end of the cylinder, and connections for rotating the abutments from the eccentrics 20 and meditately rotating the valves, said connections comprising rods loosely connecting the valve-stems and abutment-shaft cranks, and rods connecting the latter cranks with the eccentrics, the connections between the 25 abutment-shafts and the eccentric-connecting rods being slidable.

In testimony whereof I have signed this specification in the presence of two subscribing witnesses.

EUGENE H. HOLDEN.
